UNITED STATES PATENT OFFICE.

CORNELIUS W. VAN RANST, OF DETROIT, MICHIGAN.

FUEL SYSTEM.

Application filed April 15, 1922. Serial No. 553,283.

To all whom it may concern:

Be it known that I, CORNELIUS W. VAN RANST, a citizen of the United States, and a resident of Detroit, county of Wayne, and State of Michigan, have invented a certain new and useful Fuel System; and I do hereby declare that the following is a full, clear, and exact description thereof, reference being had to the accompanying drawings, in which like numerals refer to like parts.

This invention relates to the fuel system of an internal combustion engine.

The chief object of the invention is to provide an improved fuel vaporizing system for an internal combustion engine wherein the mixture supplied to the engine will be free and clean burning, from which the heavier particles have been separated by their own inertia and gravity and vaporized by a special stove construction heated from the exhaust of the motor.

Another object of the invention is to provide the fuel system with a stove construction, which stove construction preferably is heated by the exhaust.

Another object of the invention is to construct the several elements of the internal combustion engine associated with the intake and exhaust thereof so that the same may be readily detachable.

Other features of the invention, in addition to the accomplishment of the foregoing objects, will be described in detail hereinafter.

The full nature of the invention will be understood from the accompanying drawings and the following description and claims.

In the drawings, Fig 1 is a horizontal sectional view of a portion of the cylinder head of an engine. Fig. 2 is a vertical transverse sectional view of the fuel system of an internal combustion engine. Fig. 3 is an enlarged end view of the vaporizer.

In the drawings 10 indicates the usual cylinder block which is supported by the usual crank case 11. The cylinder block in turn supports the detachable cylinder head 12. The engine herein illustrated is of the four-cylinder type and is provided with the exhaust ports 13 which communicate with the exhaust chambers 14; in turn communicating with the cylinder. Each cylinder is also provided with an inlet valve port 15, and said intake ports are positioned in a header, the walls of which are indicated by the numeral

16. Positioned centrally in the header is a conduit portion 17. Positioned within the cylinder block 10 and herein extending substantially vertical therein is a conduit or standpipe 19, the upper end of which communicates with the conduit 17. Herein the standpipe 19 is shown as extending through the cylinder block. It may, however, terminate short thereof and include the construction hereinafter described as associated with the crank case. A conduit 19 may be inclined to the horizontal, but herein is shown vertical.

Extending transversely of the crank case 70 is a pipe or conduit 20 which is provided with a rectangularly positioned conduit branch 21, forming substantially a T connection. The conduit 21 herein communicates with the lower end of the conduit 19 75 and at substantially right angles to each other. The lateral pipe construction, therefore, includes the three communicating conduits 17, 19 and 21, and although herein said conduit portions are shown separable, the 80 same may be formed of a single channel and positioned entirely in the cylinder block or head or both. One branch of the conduit 20 is closed by a pipe 22 suitably secured thereto, and said pipe leads to the carburetor and 85 may form a part of the carburetor construction if desired. Upon the suction stroke there is a partial vacuum created in the cylinder and atmospheric pressure forces the carbureted mixture through the passages 22, 90 20, 19, 17 and 16. Inertia of the mass causes the heavier fuel particles to continue through the pipe 20 towards the stove and vaporizer construction at the other end. The lighter particles and carbureted air continues 95 through the lateral pipe 19 and gravity here separates the heavier fuel particles from the carbureted mixture. The mixture which ultimately reaches the inlet valves is, therefore, readily combustible.

The burned gases are exhausted from the chambers 14 through the ports 13 into the communicating pipes or connections 23, forming a part of the exhaust manifold 24. The exhaust manifold 24 is provided with a pipe 25 which is herein illustrated as discharging into a stove construction, which in turn discharges into the exhaust pipe 26. The stove construction mentioned is positioned in the exhaust pipe substantially opposite the other branch of the T conduit 20.

Herein the stove construction is illustrated as a heater casing 27 having openings 28 and 29 therein which register with the exhaust pipes 25 and 26 respectively and to 5 which they are secured. The heater casing 27 is provided with an opening 30 which is enlarged at 31 to form a shoulder 32. The opening 30 is adapted to register with the other branch of the conduit 20. Suitable 10 bolts 33 are adapted to secure the heater to the motor, so that the opening 30 registers with the conduit 20. The heater casing is also provided with an opening 34 which herein is shown threaded. The opening 34 15 permits access to the interior of the heater casing.

Positioned within the casing 27 and extending into the conduit 20 is a vaporizer unit having a shouldered flange 35 which is 20 engageable upon the shoulder 32 in the opening 30. The vaporizer unit comprises a projecting portion 36 which extends inwardly into the conduit 20 and is frusto-conical. The frusto-conical projection in 25 turn is hollowed out to form a conical recess 37 positioned axially thereof. The heat abstracting portion of the vaporizer, see Figs. 2 and 3, comprises a plurality of parallel fins 38. Positioned centrally of said fins 30 and the vaporizer is an abutment extension 39. A plug 40 having a threaded portion for engagement with the threaded opening 34 is also provided with an abutment 41. By screwing the plug 40 into the opening 25 34, the abutment 41 engages the abutment 39 and forces the vaporizer into engagement with the heater casing 27, so that the shouldered flange 34 will be seatable in the shouldered opening 30 and be secured in 40 said opening with a leak-proof joint. The plug 40, thus, not only secures the vaporizer unit in position, but also permits said vaporizer unit to be removed from the heater casing or stove, so that the carbon upon 45 the fins 38 may be removed therefrom, carbon being a poor conductor of heat.

As shown clearly in Fig. 2, the construction and arrangement of the parts is such that the incoming fuel is forced into the 50 conduit 20 and the heavier liquid particles impinge upon the projecting portion of the vaporizer and particularly upon the conical exterior and interior surfaces hereinbefore described. Likewise, any liquid fuel separated by gravity which has been discharged from the standpipe 19 into the conduit 20 55 will also impinge upon the vaporizer projection. When the liquid fuel impinges upon the vaporizer projection, the same causes the fuel to vaporize, since the vaporizer unit is heated from the exhaust gases through the agency of the fins 38. If desired, the conduit 20 may be tilted in such a manner that the liquid fuel normally will 60 run towards the vaporizer projection, but

ordinarily the same is not necessary, since the liquid fuel in the conduit 20 will be thrown towards the vaporizer by the crown of the roadway and the velocity of the incoming gases.

The aforesaid construction is such that it only vaporizes the liquid fuel without heating the incoming mixture to any appreciable degree, thereby retaining the high volumetric efficiency, due to a cold mixture.

While the invention has been described in considerable detail in the foregoing specifications and several modifications thereof have been suggested, said modifications as well as others which may readily suggest themselves to those skilled in the art to which the invention applies are all considered to be within the broad purview of this invention, as outlined by the appended claims.

The invention claimed is:

1. In an internal combustion engine, the combination of an included inverted T-shaped fuel supplying channel therein, a vaporizer connected to one arm of the T, a carburetor connected to the other arm thereof, and a header connected to the base of the inverted T-shaped channel and to the engine cylinders.

2. In an internal combustion engine, a conduit extending therethrough substantially parallel to the cylinders, a conduit extending longitudinally of the engine and connected to each cylinder and the substantially parallel conduit and substantially transverse to said substantially parallel conduit, and another conduit extending laterally through the engine and substantially transverse to the substantially parallel conduit and connected thereto intermediate the transverse conduit ends.

3. In an internal combustion engine, a conduit extending therethrough substantially parallel to the cylinders, a conduit extending longitudinally of the engine and connected to each cylinder and the substantially parallel conduit and substantially transverse to said substantially parallel conduit, another conduit extending laterally through the engine and substantially transverse to the substantially parallel conduit and connected thereto intermediate the transverse conduit ends, and means connected with both ends of the third-mentioned conduit for supplying a completely vaporized and atomized fuel to the cylinders.

4. In an internal combustion engine, the combination of a transversely extending conduit, another conduit positioned at an angle to the engine base communicating with said transversely extending conduit, a fuel supply line communicating with one end of the transversely extending conduit, and a vaporizer positioned in the other end of the transversely extending conduit.

5. A vaporizer construction comprising a casing including a chamber provided with a pair of openings for including said casing in the exhaust of an engine, a heat absorbing construction positionable in said casing, said casing having an additional opening therein, and a plug for closing said last mentioned opening and for maintaining said construction in position in said casing.
6. A vaporizer unit including an end portion comprising a plurality of fins, an intermediate supporting portion, and an opposite end portion comprising a frusto-conical projection provided with an axially aligned conical depression. ¹⁰
